FIG. I

FIG. II

FIG. III

INVENTOR
KENNETH STANLEY

BY *George C. Sweeney*

UNITED STATES PATENT OFFICE

2,386,011

CONNECTOR WRENCH

Kenneth Stanley, North Hollywood, Calif., assignor, by mesne assignments, to Lockheed Aircraft Corporation, a corporation of California

Application January 29, 1943, Serial No. 474,015

1 Claim. (Cl. 81—90)

This invention relates to a connector wrench and more specifically to wrenches adapted to be used on electrical conduit connectors when such connectors are in a comparatively inaccessible location.

Prior to this invention, due to the nature of the construction usually surrounding conduit connectors, many injuries were sustained by individuals due to the slipping of conventional wrenches from the head of thin locking nut used with said connectors. Also due to the usual inaccessibility of such connectors, the present wrenches are not adequate to perform the operation required, therefore I provide as an object of my invention a novel means of overcoming the aforesaid disadvantages of the herebefore used wrenches.

Another object of this invention is to provide a novel means of locating a connector wrench in proper operating position during the use thereof.

Other and further important objects of this invention will be apparent from the disclosures in the specification and the accompanying drawing.

This invention in its preferred form is illustrated in the drawing and hereinafter more fully described.

In the drawing—

Figure I is a bottom plan view of one form of the wrench particularly adapted for use on connectors entering through the sides of an outlet box.

Figure II is a side elevation, partially in section, of the wrench shown in position of operation with a conduit connector; and

Figure III is a side elevation of an alternate arrangement of the wrench suitable for use with conduits entering through the bottom of an outlet box.

A connector wrench of the type used on electrical conduit connections has a handle 11, one end 12 of which is provided with a conically tapered pilot plug 13, its lower edges being beveled and having its sides machined to the width of the extending arm 12 as at 14. On the lower side of handle 11 near the end 12, I arrange a nut engaging member 15 secured to the handle 11 by suitable means as for instance by welding as indicated at 16. The nut engaging member 15 has a flat surface to engage one flat of a nut 18 and is also provided with a V shaped slot 17 which is adapted to engage a corner of the nut. Such a nut threadily engages on a connector sleeve 19, extending through an opening in an

outlet box wall 20. The connector sleeve is formed as part of a shielded conduit 21 and has a collar 22 to engage around the outlet box aperture through which the sleeve 19 extends.

5 Thus it will be seen that by inserting the pilot plug 13 into the open end of sleeve 19, the nut engaging member 15 will engage either a flat or a corner of the nut 18, and by turning the handle 11, the nut 18 may be drawn down to 10 any desired tension. By arranging to drive the nut from either a flat or a corner thereof the wrench can work in close corners of a conduit outlet box since the wrench can be used either way, or alternately if the swing room is especially 15 limited. This particular arrangement of a connector wrench is especially adapted to be used on conduit connector nuts when such nuts are in a position accessible only from one side with limited clearances elsewhere, as when the conduit extends through a side wall of the outlet 20 box.

As an alternate arrangement (see Figure III) I provide an upright rod 23 which has a turning handle 24, extending through the upper end thereof. The lower end of rod 23 is attached to an inverted U shaped member 25 by any suitable means, as for instance, by welding as indicated at 26, and has two nut engaging legs 27 which are adapted to engage two opposite flats of a nut. Positioned on the lower side of the U shaped member 25 and intermediate the legs 27 I have arranged a pilot post 13' which is similar to pilot post 13 heretofore described.

In either form of this invention the pilot 13 serves to center the wrench relative to the conduit sleeve and thus prevents slippage of the wrench with consequent bruising of the operator's hand. The form of wrench shown in Figure II can readily be engaged and disengaged from successive corners of the nut being tightened so that a rapid ratchet action is possible in cramped quarters where only a small angular swing can be given to the wrench at each engagement thereof with the nut.

45 This alternate arrangement may be adapted for use on conduit connectors where said connectors are easily accessible from the top but afford limited side accessibility.

Having thus described my invention and the present preferred embodiments thereof, I desire to emphasize the fact that many modifications may be resorted to in a manner limited only by a just interpretation of the following claim.

I claim:

50 A wrench adapted to be used to screw a thin

polygonal nut along a threaded electrical conduit sleeve projecting into an outlet box in a comparatively inaccessible location, the wrench including a handle of uniform cross section, a forwardly projecting portion of reduced thickness formed integral with one end of the handle, a conically tapered plug attached adjacent the end of said forwardly projecting portion and adapted to be entered into the open end of the sleeve to form a centering pivot for the wrench when the handle is swung, and a nut engaging

member rigidly attached to and presenting a flat surface flush with the end of said handle adjacent the said conically tapered plug, said flat surface being provided with a V-shaped slot and being related to said conically tapered plug to engage a facet of the nut against the flat surface or a corner of the nut in the V-shaped slot for screwing the nut along the sleeve upon operation of the handle.

10

KENNETH STANLEY.
